UNITED STATES PATENT OFFICE.

WILLIAM A. BRADLEY, OF NEW YORK, N. Y.

DESIGN FOR A TOILET-POWDER RECEPTACLE.

No. 37,819.

Specification for Design.

Patented Feb. 13, 1906.

Application filed December 29, 1905. Serial No. 293,868. Term of patent 7 years.

To all whom it may concern:

Be it known that I, WILLIAM A. BRADLEY, a citizen of the United States, and a resident of the city of New York, borough of Manhattan, in the county and State of New York, have invented a new, original, and ornamental Design for a Toilet-Powder Receptacle, reference being had to the accompanying drawings.

Figure 1 is a perspective view of a toilet-

powder receptacle, showing my new design; and Fig. 2 is a plan view of the same.

I claim—

The ornamental design for a toilet-powder receptacle as shown.

WILLIAM A. BRADLEY.
